PROCESS AND APPARATUS FOR INJECTING
FLUID INTO A WELLWilliam B. Belknap, Bartlesville, Okla., assignor to Phillips Petroleum Company, a corporation of Delaware
Filed Mar. 9, 1964, Ser. No. 350,254
13 Claims. (Cl. 166—40)

This invention relates to a process and apparatus for injecting a fluid into a well thru a tubing string having a pump on the lower end without removing the pump from the well.

The production of oil from subterranean oil-bearing strata thru production wells having a tubing string and a pump on the lower end thereof frequently requires injection of fluid into the well. An illustration of this situation is in the injection of steam into an oil well to heat the oil-bearing stratum to increase oil production or flow of oil into the well. In one technique of operation, superheated steam is injected into the well and after an extended heating period with steam, the oil flowing into the well is produced by conventional pumping means. The injection of steam is then renewed to cause more oil to flow into the well and after an extended heating period, the oil in the well is again pumped to the surface. In this alternating heating and production technique, it has been considered necessary to pull the pump out of the well in order to inject steam into the stratum. In some applications of this method it has even been necessary to pull the tubing string for the steam injection phase of the operation.

This invention is concerned with a method and means of injecting a fluid into an oil-bearing stratum thru a tubing string having a pump on the lower end without pulling the pump from the well.

Accordingly, it is an object of the invention to provide a process and apparatus for alternately injecting steam or other heating fluid into an oil-bearing stratum thru a tubing string in a well having a pump in the lower end of the tubing string, to heat and cause oil to flow into the well and thereafter pumping the oil from the well without withdrawing the pump and rods from the well. Another object is to provide a simple method and apparatus for injecting a fluid into a production well having a pump in the lower end of a tubing string therein without pulling the pump from the well. Other objects of the invention will become apparent to one skilled in the art upon consideration of the accompanying disclosure.

A broad aspect of the invention comprises providing an expanded section of tubing in the tubing string just above the pump on the lower end of the string, said section being of greater length and internal diameter than the length and external diameter of the pump or pump plunger so that a passageway is formed around the pump or plunger when retracted into the expanded section, retracting the pump into the expanded section when injection of fluid is desired, and injecting fluid thru the tubing into the bottom of the well and into the surrounding stratum. In applications of the invention in which a tubing type pump is utilized, the working barrel of the pump is attached to the lower end of the tubing and the plunger is suspended on the lower end of the sucker rod and it is necessary to utilize a pump of this type which includes a standing valve retractable with the plunger. Pumps of this type are conventional and available from various manufacturers. In another application of the invention, a rod pump or insert pump is utilized in which the complete unit, both the plunger and the working barrel, is lowered into a well on the lower end of the sucker rod and the complete unit is retractable into the expanded section so as to permit unobstructed flow of injected fluid thru the tubing string around the

pump and into the bottom of the well. With either type of pump, all that is necessary is to lift the sucker rod sufficiently to position the pump or pump plunger within the expanded joint or section of tubing so as to provide a fluid flow path around the pump or plunger and then inject the steam or other heating fluid thru the tubing string for any suitable heating period.

Superheated steam at a temperature in the range of 300 to 750° F. is the preferred heating medium. However, hot water, hot hydrocarbons (normally liquid or normally gaseous), hot gases, such as air, flue gas, O₂, or nitrogen, as well as other gaseous and liquid media may be injected in accordance with the invention. In the ensuing discussion of the invention, steam will be the injected heating medium.

When injecting steam at a temperature in the range of 300 to 750° F. and, particularly, at 550° F. there is a substantial expansion of the tubing string up to 15' or more, depending upon the depth of the producing zone which determines the length of the tubing string. In one application of the steam injection and pumping process the expansion of the tubing string amounts to approximately 12'. This means that provision must be made for slippage of the tubing string thru the packer used to pack off the casing-tubing annulus just above the expanded section of tubing. Packing off this annulus is practiced in order to decrease the loss of heat to the surrounding overburden and problems which would occur with resulting expansion of the casing.

A more complete understanding of the invention may be had by reference to the accompanying schematic drawing of which FIGURE 1 is an elevation in partial section showing a preferred arrangement of the apparatus of the invention; FIGURE 2 is a horizontal section taken on the line 2—2 of FIGURE 1; and FIGURE 3 is an elevation in partial section of apparatus similar to FIGURE 1 utilizing another type of pump.

Referring to FIGURE 1, an oil-bearing stratum 10 is penetrated by a well 12 which is provided with a case 14 extending approximately to the top of the stratum from a well head 16. A tubing string 18 extends thru the well head and thru stratum 10. A pump 20 comprising a working barrel 22 and a plunger 24 is positioned on the lower end of tubing string 18, the plunger 24 being attached to sucker rod string 26. The standing valve 28 of the pump is seated on seat 30 so as to form a seal therewith and is retractable with plunger 24 when it is desired to retract the plunger as hereinafter described. Pump 20 is a conventional tubing pump available from different manufacturers. It must be of the type in which the standing valve is retractable with the plunger and detachably connected thereto by a threaded or J-lock joint.

An enlarged or expanded section or joint of tubing 32 is provided above and close to pump 20 so that plunger 24 with standing valve 28 may be attached thereto and may be withdrawn or retracted to the position illustrated by dotted lines within section 32. In the retracted position the annulus 36 between pump plunger 24 and tubing section 32 provides a passageway for fluids injected thru the tubing string into the bottom of the well and into stratum 10.

Packer 38 is preferably set just above tubing section 32 and is a type available commercially which allows substantial movement of tubing 18 vertically thru the packer. In one embodiment, this packer is about 22' long and provides about 15' of slippage of tubing 18 while still maintaining the desired seal between the packer and the tubing. In the same embodiment of the invention pump 20 has a 12' stroke utilizing a plunger 2¾" O.D. operating in a 3" I.D. tubing string and tubing type pump barrel. Tubing section 32 has a 4" I.D. so that annulus

36 is $\frac{5}{8}$ ", thereby providing adequate flow path for injected fluids around pump 20 when retracted to the injection position in conduit 32. Tubing section 32 is positioned close to pump 20 and connected thereto by a short section of standard 3" tubing 40 so as to minimize the required distance for moving pump 20 into tubing section 32. This makes it feasible to retract the pump or pump plunger with the pumping unit at the well head without the use of a conventional pulling unit.

It is also within the scope of the invention to position tubing section 32 above packer 38 as shown in dotted lines in this position. In such a case packer 38 would be located just above pump 20.

In unconsolidated strata, a perforated linear 42 is positioned in the bottom of the well within stratum 10 to minimize sand influx into the well with the produced oil. In some oil-bearing formations such as unconsolidated sands the perforated linear 42 is packed with a coarse gravel to further minimize sand production.

Referring to FIGURE 2, pump or pump barrel 24 is shown in retracted position within expanded tubing section 32 providing annulus 36 between the inner wall of the tubing section and the outer wall of the pump. Sucker rod 26 connects with the top of the pump.

In FIGURE 3, corresponding elements to those in FIGURE 1 are correspondingly numbered. A rod type pump 50 comprises working barrel 52, traveling barrel 54, traveling valve 56 in the lower end of traveling barrel 54, and standing valve 58 in the bottom of working barrel 52. A seat and hold down 60 in the bottom of the pump and tubing section 62 cooperate to seal the bottom end of tubing section 62 and hold the working barrel of the pump in the bottom thereof. Positioning of traveling valve 56 in the lower section of traveling barrel 54 is preferred when the well produces any appreciable amount of gas, since this type of pump is more resistant to gas lock.

Pump 50 is readily retractable from pumping position into tubing section 32 by applying pulling force on sucker rod string 26 and lifting the pump into the retractable position illustrated in dotted lines within section 32.

Either the pump plunger illustrated in FIGURE 1 or the rod pump illustrated in FIGURE 3 is easily retractable into the expanded tubing section to permit injection of fluid into the producing well in which it is positioned. In operating in accordance with the invention, steam, preferably at an elevated temperature in the range of 300 to 750° F. is injected thru the tubing string with the pump in retracted position and the steam injection is continued until a substantial amount of oil has been caused to flow into the well by the heating produced by the steam. Obviously, heat applied to the producing formation renders the oil therein less viscous and more readily flowable so that a substantial amount of the more fluid oil flows into the well. After this has occurred, the steam injection is terminated and the pump is lowered into pumping position so that pumping can take place to remove the oil from the well. After the flow of oil into the well has become insufficient to warrant further pumping, the pump plunger or pump pre se is again retracted to the desired position in the expanded section of the tubing string and injection of steam is resumed. This alternate steaming and production is continued until the process is no longer economically feasible.

The invention is applicable to the production of oil from various types of oil-bearing strata but it is especially applicable to formations containing highly viscous crude such as are found in Monagas, Venezuela, and in certain areas of the United States and Canada. It is also applicable to the production of tar sands and shales which have sufficient permeability to permit steam injection or which have been fractured to provide for steam injection. In some formations containing highly viscous crudes, the injected steam not only causes oil to flow into the well but also renders the crude readily pumpable whereas,

without substantial heating of the crude, it is not readily pumpable.

Expansion of the tubing string during steam injection is accommodated by slippage thru the packer. There will be a lesser amount of expansion of the casing and this expansion is effected upwardly. Accommodation of casing expansion is made in the bradenhead where slippage thru the packing gland results.

Certain modifications of the invention will become apparent to those skilled in the art and the illustrative details disclosed are not to be construed as imposing unnecessary limitations on the invention.

I claim:

1. A process for producing oil from an oil-bearing stratum penetrated by a well having a casing extending to said stratum and a tubing string into said stratum from a well head at ground level which comprises the steps of:

- (1) providing a pump in pumping position in the lower end of said tubing string slidably sealed therein;
- (2) providing an enlarged section of tubing in said tubing string above the pumping position of said pump for housing said pump in retracted position and providing a flow annulus between said pump and the wall of said enlarged section;
- (3) alternately injecting hot fluid into said stratum thru said tubing and said flow annulus with said pump in retracted position and pumping liquid accumulating in said well with said pump sealed in pumping position, thereby alternately heating and causing oil to flow into said well and pumping the produced oil to ground level.

2. The process of claim 1 wherein said hot fluid is steam.

3. The process of claim 1 wherein said hot fluid is hot water.

4. The process of claim 1 wherein said hot fluid is hot gas.

5. A process for producing oil from an oil-bearing stratum penetrated by a well having a casing extending to said stratum and a tubing string into said stratum from a well head at ground level which comprises the steps of:

- (1) providing a pump in pumping position in the lower end of said tubing string slidably sealed therein;
- (2) providing an enlarged section of tubing in said tubing string above the pumping position of said pump for housing said pump in retracted position and providing a flow annulus between said pump and the wall of said enlarged section;
- (3) injecting steam thru said tubing into said stratum with said pump in retracted position until a substantial amount of oil in said stratum around said well is rendered less viscous, flows into, and accumulates in said well;
- (4) thereafter, lowering said pump into pumping position and pumping the accumulated oil to ground level.

6. The process of claim 5 wherein steps (3) and (4) are alternately repeated.

7. A process for injecting a fluid into a well thru a tubing string therein, having a sucker rod carrying pumping means removably sealed in the lower end of the tubing string, without pulling the rod and pumping means from the tubing, which comprises the steps of:

- (1) providing an expanded section of tubing above said pumping means and near the lower end of said tubing, having an internal diameter and length substantially greater than the external diameter and length of said pumping means, so that when said pumping means is pulled into said section a flow path around same within said tubing is formed;
- (2) retracting said pumping means into said section of tubing so as to form said flow path; and

- (3) injecting a fluid thru said tubing into said well while said pumping means is in said expanded section.
3. The process of claim 7 wherein said fluid is a heating fluid.
9. The process of claim 7 wherein said fluid is steam.
10. Apparatus in an oil well having a casing and well head and penetrating an oil-bearing stratum comprising in combination:
- (a) a tubing string extending thru said well head into said stratum;
  - (b) a section of tubing in the tubing string of (a) of substantially larger internal diameter than the adjacent tubing and substantially longer than the pump means of (c), said section being near the bottom end of said tubing string;
  - (c) a pump means in the tubing string of (a) attached to the lower end of a sucker rod extending from the well head to the lower end of the tubing string, said pump means being alternately movable into pumping position sealed with the wall of said tubing string below said section and then into said section to provide a passageway around said pump means and thru the lower end of said tubing for injecting fluid thru said tubing string and around said pump means into said stratum.

- 5 11. The apparatus of claim 10 wherein said casing extends substantially to said stratum and including a packer around said tubing string adjacent said section closing off the annulus between said casing and said tubing string, said tubing string being slidably sealed with said packer to provide for expansion of said tubing string when hot fluid is injected therethru.
- 10 12. The apparatus of claim 10 wherein said pump means comprises a rod pump removable with said rod.
13. The apparatus of claim 10 wherein said pump means comprises a tubing pump having a standing valve removable with the pump plunger attached to said rod.
